TELEPHONE SYSTEM

Clarence E. Lomax, Oak Park, Ill., assignor to Associated Electric Laboratories, Inc., Chicago, Ill., a corporation of Delaware

Application December 24, 1938, Serial No. 247,603

33 Claims. (Cl. 179—41)

The present invention relates to signaling systems and more particularly to telephone systems comprising a number of remotely disposed exchanges interconnected by trunk lines.

A telephone system conventionally comprises two or more main exchanges and one or more auxiliary exchanges interconnected by trunk lines terminating at operator positions in the respective exchanges. Usually, one or more through trunk lines extend between the two main exchanges; and one or more branch trunk lines extend between the auxiliary exchange and a central point disposed intermediate the two main exchanges, the branch trunk lines being tapped onto the respective through trunk lines. Ordinarily, each operator position is of the manual type and comprises suitable apparatus for setting up trunk connections by way of any one of the trunk lines terminating thereat.

While reasonably satisfactory trunk service may be rendered in a telephone system of the type described, there are several objectionable features thereto. In the first place, the operator positions disposed in the three exchanges mentioned are interconnected by each trunk line, rendering it necessary to employ code ringing in the system in order that a calling operator may indicate to the other two operators which one of them is the called operator. A more seriously objectionable feature of the system resides in the fact that the portion of each through trunk line disposed on either side of a tapped point and the branch trunk line connected to the through trunk line at the tapped point are electrically interconnected. Accordingly, a fault upon the branch trunk line renders the through trunk line out of service. Likewise, a fault on either of the portions mentioned of the through trunk line renders the branch trunk line out of service. Moreover, the branch trunk line unnecessarily increases the transmission losses upon the through trunk line when a trunk connection is established between the main exchanges. Likewise, one portion mentioned of the through trunk line unnecessarily increases the transmission losses upon the branch trunk line and the other portion mentioned of the through trunk line when a trunk connection is established between the auxiliary exchange and one of the main exchanges.

Accordingly, it is an object of the present invention to provide, in a telephone system of the type described, an improved arrangement for interconnecting at a switching center inde-

pendent trunk lines extending between the switching center and a number of exchanges.

Another object of the invention is to provide, in a telephone system comprising a number of exchanges and a switching center, an improved arrangement controlled over a calling trunk line extending between one of the exchanges and the switching center for selectively associating the calling trunk line with other of the trunk lines extending between the switching center and other of the exchanges.

A further object of the invention is to provide, in a telephone system of the type noted, an improved switching arrangement and control arrangement therefor at the switching center for selectively interconnecting the trunk lines extending between the switching center and the exchanges.

The features of the present invention are illustrated as being incorporated in a telephone system comprising a switching center, three exchanges and trunk lines extending between the switching center and the respective exchanges, each of the trunk lines comprising two line conductors, one end of each trunk line being terminated in a repeater at the switching center and the other end thereof being terminated in a repeater in the exchange to which the trunk line extends. Also an operator position is arranged in each of the exchanges and provided with suitable apparatus for initiating and answering trunk calls and for setting up trunk connections over the trunk lines extending to the associated exchange. Furthermore, switching apparatus is provided at the switching center which is selectively operative to associate any one of the repeaters thereat with two other of the repeaters thereat, thereby selectively and operatively to connect the trunk line terminated by the one repeater to the two trunk lines terminated by the two other repeaters.

In accordance with one feature of the invention, the switching apparatus at the switching center comprises a plurality of relay devices respectively associated with the repeaters at the switching center and individually provided with control apparatus. More particularly, each of the control apparatus includes a circuit network; and each of the relay devices comprises two relays respectively provided with operating windings, the operating windings of the two relays being so connected and arranged in the associated control apparatus that the two relays are selectively operative in accordance with the direction of current flow in the circuit network of

the associated control apparatus. In a given relay device, one of the relays is operative to cause the associated repeater at the switching center to be associated with another repeater thereat; while the other of the relays is operative to cause the associated repeater at the switching center to be associated with a further repeater thereat. Accordingly, the given relay device is selectively operative to connect the trunk line terminated by the associated repeater operatively and selectively to the two trunk lines terminated respectively by the other and the further repeaters mentioned.

Moreover, the circuit network of each of the control apparatus is provided with two terminals, one of which is connected to ground and the other of which is connected to a corresponding simplex link provided by the associated repeater at the switching center, the trunk line terminated by the last-mentioned repeater and the repeater in the exchange to which the last-mentioned trunk line extends.

In accordance with another feature of the invention the control apparatus provided at each operator position comprises a cord circuit including a telephone instrument and talk and ring keys, means for operatively associating the cord circuit with the trunk line extending to the associated exchange and means for selectively connecting the ungrounded positive terminal of a grounded source of current and the ungrounded negative terminal of a grounded source of current to the simplex link provided by the toll line extending to the associated exchange. More particularly two call jacks are provided at the operator position and associated with a loop circuit extending to the repeater in the associated exchange terminating the trunk line extending thereto; and the cord circuit at the operator position is provided with a plug. When the plug of the cord circuit is selectively inserted into the two call jacks the cord circuit, and consequently the telephone instrument therein, are operatively associated by way of the loop circuit and the repeater with the trunk line extending to the associated exchange and the positive and negative terminals of the sources of current are selectively connected to the simplex link mentioned, thereby selectively to determine the direction of the current conducted to the circuit network of the control apparatus connected to the simplex link. Also, the ring and talk keys in the cord circuit are operative respectively to control the projection of alternating signal current over the trunk line extending from the exchange and over the trunk line operatively associated with the last-mentioned trunk line at the switching center and to control the connection of the telephone instrument in the cord circuit to the loop circuit mentioned. Furthermore, an answer jack and a signal are provided at each operator position for the respective purposes of answering a trunk call extended to the associated exchange and of signaling the operator when a trunk call is extended to the associated exchange.

Further features of the invention pertain to the particular arrangement of the circuit elements thereof, whereby the above-outlined and additional features are attained.

The novel features believed to be characteristic of the invention are set forth with particularity in the appended claims. The invention, both as to its organization and method of operation, together with further objects and advantages thereof, will best be understood by reference to the 75

following specification taken in connection with the accompanying drawing, in which the single figure illustrates diagrammatically a telephone system having embodied therein the features of the present invention.

Referring now more particularly to the drawing, the telephone system there illustrated comprises a switching center 10, three remotely disposed manual telephone exchanges A, B and C and three toll or trunk lines 80, 70 and 60, respectively extending between the switching center 10 and the exchanges A, B and C. Each of the toll lines is of the two-way type and the opposite ends thereof are terminated in repeaters disposed at the switching center 10 and in the exchange to which the toll line extends. More particularly, the ends of the toll lines 60, 70 and 80 extending to the switching center 10 are terminated in the repeaters 64, 74 and 84, respectively, disposed at the switching center 10; while the ends of the toll lines 60, 70 and 80 extending to the exchanges C, B and A are respectively terminated in the repeaters 13, 17 and 15 disposed in the respective exchanges. A toll operator position in each of the exchanges is operatively associated with the repeater in the exchange terminating the toll line extending thereto. More particularly, the toll operator positions 14, 16 and 12 in the exchanges A, B and C, respectively, are operatively associated with the repeaters 15, 17 and 13, respectively terminating the toll lines 80, 70 and 60 extending to the respective exchanges.

The repeaters 84, 74 and 64 at the switching center 10 are operatively associated with a switching network thereat including three groups of relays, each group comprising two relays. More particularly, the repeater 84 is operatively associated with a group of relays comprising the relays R90 and R95; the repeater 74 is operatively associated with the group of relays comprising the relays R110 and R115; and the repeater 64 is operatively associated with the group of relays comprising the relays R100 and R105. A unidirectional current conducting device in the form of a copper oxide rectifier is connected in parallel circuit relationship with the winding of each of the relays R90, R95, R100, etc., the devices 91, 96, 101, 106, 111 and 116 being respectively connected in parallel circuit relationship with the windings of the relays R90, R95, R100, R105, R110 and R115. A circuit including a simplex link is provided for controlling the energization of the two relays in each of the groups, in a manner more fully described subsequently. The circuit for controlling the energization of the relays R90 and R95 comprising one of the groups includes a simplex link provided by the toll line 80 and the repeaters 15 and 84 associated therewith; the circuit for controlling the energization of the relays R100 and R105 comprising another of the groups includes a simplex link provided by the toll line 60 and the repeaters 13 and 64 associated therewith; and the circuit for controlling the energization of the relays R110 and R115 comprising another of the groups includes a simplex link provided by the toll line 70 and the repeaters 17 and 74 associated therewith. It is noted that the switching network at the switching center 10 is so connected and arranged that it is operative under the control of the toll operator in any one of the exchanges to connect the toll line extending to the one exchange to either one of the toll lines extending to the other exchanges.

Each of the toll operator positions in the exchanges A, B and C may be identical to the toll operator position 12 in the exchange C, which comprises two call jacks 30 and 40, an answer jack 20, a signal 24 and a cord circuit 50 of conventional connection and arrangement and provided with talk and ring switches or keys, not shown, a telephone instrument, not shown, and a plug 51 adapted to be selectively inserted into the jacks 20, 30 and 40. It is noted that the jack 20 at the operator position 12 comprises means for controlling the operation of the signal 24 thereat; while the jacks 30 and 40 comprise means for controlling the operation of the relays R100 and R105 in one of the groups in the switching network at the switching center 10. Similarly, the respective jacks at the toll operator positions 14 and 16 comprise means for controlling the signals thereat and means for controlling the operation of the relays in the other groups in the switching network at the switching center 10. More particularly, the jacks noted at the toll operator position 14 comprise means for controlling the operation of the relays R90 and R95 comprising one of the groups in the switching network at the switching center 10; while the jacks noted at the toll operator position 16 comprise means for controlling the operation of the relays R110 and R115 comprising another of the groups in the switching network at the switching center 10.

The connection and arrangement of the telephone system will best be understood from a consideration of the following description of the operation of the apparatus incorporated therein in order to establish connections between the various toll lines in the system.

A call which is to be extended from the exchange C to the exchange A is initiated by the toll operator at the operator position 12 in the exchange C upon inserting the plug 51 of the cord circuit 50 thereat into the call jack 30. When the plug 51 is inserted into the call jack 30 the switch springs 33 and 34 thereof are actuated into engagement, thereby to connect the negative terminal of the battery 35, the positive terminal of which is grounded, to the conductor C27. When the ungrounded negative terminal of the battery 35 is connected to the conductor C27 a circuit including a simplex link provided by the toll line 60 and the repeaters 64 and 13 associated therewith is completed for energizing the relay R100. The last-mentioned circuit extends from the grounded positive terminal of the battery 35 by way of the conductor C109, the rectifier 106, the winding of the relay R100, and the conductor C63 to the neutral point between the windings 67 and 68 of the repeater 64, and from the negative terminal of the battery 35 by way of the switch springs 34 and 33 of the call jack 30 and the conductor C27 to the neutral point between the windings 37 and 38 of the repeater 13, the neutral points mentioned being connected together by way of a simplex circuit extending from the first-mentioned neutral point by way of the winding 67 of the repeater 64, the line conductor C61 of the toll line 60 and the winding 37 of the repeater 13 to the last-mentioned neutral point, and from the first-mentioned neutral point by way of the winding 68 of the repeater 64, the line conductor C62 of the toll line 60, and the winding 38 of the repeater 13 to the last-mentioned neutral point. It is noted that the rectifier 106 readily conducts current over the above-traced circuit in the direction indicated,

thereby effectively to short-circuit the winding of the relay R105; while the rectifier 106 blocks the passage of current therethrough when current is conducted over the above-traced circuit in the direction indicated. Accordingly, at this time, the relay R105 is not operated and the relay R100 is operated. Upon operating, the relay R100 completes, at RA102 and at RA103, a loop circuit extending between the windings 87 and 88 of the repeater 84 and the windings 65 and 66 of the repeater 64. The last-mentioned loop circuit extends from the conductor C120 by way of the windings 87 and 88 of the repeater 84, the conductor C123, RA103, the conductor C124, the windings 66 and 65 of the repeater 64, the conductor C121 and RA102 to the conductor C120. After inserting the plug 51 of the cord circuit 50 into the call jack 30, the toll operator at the operator position 12 actuates the talk key in the cord circuit 50, thereby to complete a loop circuit between the telephone instrument in the cord circuit 50 and the windings 36 and 38 of the repeater 13. The last-mentioned loop circuit extends from the conductor C25 by way of the windings 36 and 38 of the repeater 13, the conductor C26, the jack ring 32, the plug ring 53, the talk key and the telephone instrument in the cord circuit 50, the plug tip 52 and the jack tip 31 to the conductor C25. At this time a connection is established between the telephone instrument in the cord circuit 50 at the operator position 12 and the toll line 80 extending to the exchange A, the loop circuit, including the telephone instrument in the cord circuit 50 at the operator position 12, being operatively associated with the previously traced loop circuit, extending between the windings 87 and 88 of the repeater 84 and the windings 65 and 66 of the repeater 64, by way of a loop circuit extending from the line conductor C61 of the toll line 60 over the windings 67 and 68 of the repeater 64, the line conductor C62 of the toll line 60 and the windings 39 and 37 of the repeater 13 to the line conductor C61. Also the windings 87 and 88 of the repeater 84 are operatively associated with the windings 85 and 86 thereof connected to the toll line 80 extending to the exchange A. In the event the toll line 80 is busy at this time, voice frequency current is diverted therefrom by way of the various loop circuits previously traced to the receiver of the telephone instrument in the cord circuit 50 at the operator position 12 and the toll operator thereat hears the conversation. On the other hand, in the event the toll line 80 is idle at this time, the toll operator at the operator position 12 does not hear a conversation. The toll operator at the operator position 12 then actuates the ring key in the cord circuit 50 thereat, thereby to complete a circuit for conducting alternating ringing current over a portion of the previously traced loop circuit extending between the windings 36 and 38 of the repeater 13 and the cord circuit 50. More particularly, the alternating ringing current is conducted from one terminal of a source of alternating ringing current by way of the ring key in the cord circuit 50, the plug tip 52, the jack tip 31, the conductor C25, the windings 36 and 38 of the repeater 13, the conductor C26, the jack ring 32 and the plug ring 53 to the other terminal of the source of alternating ringing current. The alternating ringing current traversing the windings 36 and 38 of the repeater 13 induces a similar alternating ringing current in the windings 37 and 39 of the

repeater 13 which ringing current traverses the previously traced loop circuit extending between the windings 37 and 39 of the repeater 13 and the windings 67 and 68 of the repeater 64. The alternating ringing current traversing the windings 67 and 68 of the repeater 64 induces a similar alternating ringing current in the windings 65 and 66 of the repeater 64 which ringing current traverses the previously traced loop circuit extending between the windings 87 and 88 of the repeater 84 and the windings 65 and 66 of the repeater 64. The alternating ringing current traversing the windings 87 and 88 of the repeater 84 induces a similar alternating ringing current in the windings 85 and 86 of the repeater 84 which ringing current traverses a loop circuit extending between the windings of the repeater 15 and the windings 85 and 86 of the repeater 64. The alternating ringing current traversing the last-mentioned windings of the repeater 15 induces a similar alternating ringing current in the associated windings of the repeater 15 which ringing current traverses a loop circuit extending between the last-mentioned windings of the repeater 15 and the winding of the signal at the operator position 14. The alternating ringing current traversing the winding of the signal at the operator position 14 actuates the signal, thereby to indicate to the toll operator at the operator position 14 that a call is extended to the exchange A.

The toll operator at the operator position 14 answers the call by inserting the plug of the cord circuit thereat into the answer jack at the operator position 14. When the plug of the cord circuit is inserted into the answer jack at the operator position 14 the previously mentioned loop circuit for energizing the winding of the signal thereat is interrupted, thereby to arrest further operation of the signal. Finally, the toll operator at the operator position 14 actuates the talk key in the cord circuit thereat, thereby to complete a loop circuit between the windings of the repeater 15 and the telephone instrument in the cord circuit at the operator position 14. At this time a two-way communication connection is established between the telephone instrument in the cord circuit 50 at the operator position 12 and the telephone instrument in the cord circuit at the operator position 14, thereby to permit the toll operators at the operator positions 12 and 14 in the exchanges C and A, respectively, to communicate with each other in either direction.

The release of this established connection between the exchanges C and A is primarily under the control of the toll operator at the operator position 12 in the exchange C and is effected by the toll operator thereat by removing the plug 51 of the cord circuit 50 from the call jack 30. When the plug 51 is removed from the call jack 30 the switch springs 33 and 34 thereof are actuated into disengagement, thereby to interrupt the previously traced path for connecting the ungrounded negative terminal of the battery 35 to the conductor C27. When the ungrounded negative terminal of the battery 35 is disconnected from the conductor C27, the previously traced circuit including the simplex link provided by the toll line 60 and the windings of the repeaters 64 and 13 associated therewith for energizing the winding of the relay R100 is interrupted, whereupon the relay R100 restores. Upon restoring, the relay R100 interrupts, at RA102 and at RA103, the previously traced loop circuit extending between the windings 87 and 88 of the 75

repeater 84 and the windings 65 and 66 of the repeater 64. Finally, the toll operators at the operator positions 14 and 12 actuate the talk keys in the respective cord circuits thereat in order to 5 disconnect the telephone instruments therein from the plugs of the respective cord circuits at the respective operator positions.

A call which is to be extended from the exchange C to the exchange B is initiated by the toll operator at the operator position 12 in the exchange C upon inserting the plug 51 of the cord circuit 50 thereat into the call jack 40. When the plug 51 is inserted into the call jack 40 the switch springs 43 and 44 thereof are actuated into engagement, thereby to connect the positive terminal of the battery 45, the negative terminal of which is grounded, to the conductor C27. When the ungrounded positive terminal of the battery 45 is connected to the conductor C27 10 a circuit including the previously mentioned simplex link provided by the toll line 60 and the repeaters 64 and 13 associated therewith is completed for energizing the relay R105. The last-mentioned circuit extends from the ungrounded positive terminal of the battery 45 by way of the switch springs 43 and 44 of the call jack 40 and the conductor C27 to the neutral point between the windings 37 and 39 of the repeater 13, and from the neutral point between the windings 67 15 and 68 of the repeater 64 by way of the conductor C63, the rectifier 101, the winding of the relay R105 and the conductor C109 to ground, the neutral points mentioned being connected together by way of a simplex circuit extending 20 from the first-mentioned neutral point by way of the winding 37 of the repeater 13, the line conductor C61 of the toll line 60 and the winding 67 of the repeater 64 to the last-mentioned neutral point, and from the first-mentioned neutral point 25 by way of the winding 39 of the repeater 13, the line conductor C62 of the toll line 60 and the winding 68 of the repeater 64 to the last-mentioned neutral point. It is noted that the rectifier 101 readily conducts current over the above-traced circuit in the direction indicated, thereby effectively to short-circuit the winding of the relay R100; while the rectifier 106 blocks the passage of current therethrough when current is conducted over the above-traced circuit in the direction indicated. Accordingly, at this time, the relay R100 is not operated and the relay R105 is 30 operated. Upon operating, the relay R105 completes, at RA107 and at RA108, a loop circuit extending between the windings 77 and 78 of the repeater 74 and the windings 65 and 66 of the repeater 64. The last-mentioned loop circuit extends from the conductor C122 by way of the windings 77 and 78 of the repeater 74, the conductor C125, RA108, the conductor C124, the windings 66 and 65 of the repeater 64, the conductor C121 and RA107 to the conductor C122. 35

After inserting the plug 51 of the cord circuit 50 into the call jack 40, the toll operator at the operator position 12 actuates the talk key in the cord circuit 50, thereby to complete a loop circuit between the telephone instrument in the cord circuit 50 and the windings 36 and 38 of the repeater 13. The last-mentioned loop circuit extends from the conductor C25 by way of the windings 36 and 38 of the repeater 13, the conductor C26, the jack ring 42, the plug ring 53, the talk key and the telephone instrument in the cord circuit 50, the plug tip 52 and the jack tip 41 to the conductor C25. 40

At this time a connection is established be-

tween the telephone instrument in the cord circuit 50 at the operator position 12 and the toll line 70 extending to the exchange B, the loop circuit, including the telephone instrument in the cord circuit 50 at the operator position 12, being operatively associated with the previously traced loop circuit, extending between the windings 71 and 78 of the repeater 74 and the windings 65 and 66 of the repeater 64, by way of the previously traced loop circuit extending between the windings 31 and 39 of the repeater 13 and the windings 67 and 68 of the repeater 64. Also the windings 71 and 78 of the repeater 74 are operatively associated with the windings 75 and 76 thereof connected to the toll line 70 extending to the exchange B. In the event the toll line 70 is busy at this time, voice frequency current is diverted therefrom by way of the various loop circuits previously traced to the receiver of the telephone instrument in the cord circuit 50 at the operator position 12 and the toll operator thereat hears the conversation.

On the other hand, in the event the toll line 70 is idle at this time, the toll operator at the operator position 12 does not hear a conversation. The toll operator at the operator position 12 then actuates the ring key in the cord circuit 50 thereat, thereby to complete the previously traced circuit for conducting alternating ringing current over a portion of the previously traced loop circuit extending between the windings 36 and 38 of the repeater 13 and the cord circuit 50. The alternating ringing current traversing the windings 36 and 38 of the repeater 13 induces a similar alternating ringing current in the windings 37 and 39 of the repeater 13 and the windings 67 and 68 of the repeater 64. The alternating ringing current traversing the windings 67 and 68 of the repeater 64 induces a similar alternating ringing current in the windings 65 and 66 of the repeater 64 which ringing current traverses the previously traced loop circuit extending between the windings 77 and 78 of the repeater 74 and the windings 65 and 66 of the repeater 64. The alternating ringing current traversing the windings 77 and 78 of the repeater 74 induces a similar alternating ringing current in the windings 75 and 76 of the repeater 74 which ringing current traverses a loop circuit extending between the windings of the repeater 17 and the windings 75 and 76 of the repeater 74. The alternating ringing current traversing the last-mentioned windings of the repeater 17 induces a similar alternating ringing current in the associated windings of the repeater 17 which ringing current traverses a loop circuit extending between the last-mentioned windings of the repeater 17 and the winding of the signal at the operator position 16. The alternating ringing current traversing the winding of the signal at the operator position 16 actuates the signal, thereby to indicate to the toll operator at the operator position 16 that a call is extended to the exchange B.

The toll operator at the operator position 16 answers the call by inserting the plug of the cord circuit thereat into the answer jack at the operator position 16. When the plug of the cord circuit is inserted into the answer jack at the operator position 16 the previously mentioned loop circuit for energizing the winding of the signal thereat is interrupted, thereby to arrest further operation of the signal. Finally, the toll opera-

tor at the operator position 16 actuates the talk key in the cord circuit thereat, thereby to complete a loop circuit between the windings of the repeater 17 and the telephone instrument in the cord circuit at the operator position 16. At this time a two-way communication connection is established between the telephone instrument in the cord circuit 50 at the operator position 12 and the telephone instrument in the cord circuit at the operator position 16, thereby to permit the toll operators at the operator positions 12 and 16 in the exchanges C and B, respectively, to communicate with each other in either direction.

The release of this established connection between the exchanges C and B is primarily under the control of the toll operator at the operator position 12 in the exchange C and is effected by the toll operator thereat by removing the plug 51 of the cord circuit 50 from the call jack 40. When the plug 51 is removed from the call jack 40 the switch springs 43 and 44 thereof are actuated into disengagement, thereby to interrupt the previously traced path for connecting the ungrounded positive terminal of the battery 45 to the conductor C27. When the ungrounded positive terminal of the battery 45 is disconnected from the conductor C27, the previously traced circuit including the simplex link provided by the toll line 60 and the windings of the repeaters 64 and 13 associated therewith for energizing the winding of the relay R105 is interrupted, whereupon the relay R105 restores. Upon restoring, the relay R105 interrupts, at RA107 and at RA108, the previously traced loop circuit extending between the windings 77 and 78 of the repeater 74 and the windings 65 and 66 of the repeater 64. Finally, the toll operators at the operator positions 16 and 12 actuate the talk keys in the respective cord circuits thereat in order to disconnect the telephone instruments therein from the plugs of the respective cord circuits at the respective operator positions.

A call which is to be extended from the exchange A to the exchange C is initiated by the toll operator at the operator position 14 in the exchange A upon inserting the plug of the cord circuit thereat into a proper one of the call jacks thereat, thereby to cause the ungrounded positive terminal of a battery, the negative terminal of which is grounded, to be connected to a conductor, not shown, extending to the neutral point between the windings of the repeater 15, included in the previously mentioned loop circuit extending between the last-mentioned windings of the repeater 15 and the windings 85 and 86 of the repeater 84. This application of positive battery potential to the conductor mentioned completes a circuit including a simplex link provided by the toll line 80 and the windings of the repeaters 15 and 84 associated therewith for energizing the relay R90. The last-mentioned circuit extends from the positive terminal of battery by way of the conductor mentioned to the neutral point between the windings mentioned of the repeater 15 and from the neutral point between the windings 85 and 86 of the repeater 84 by way of the conductor C83, the winding of the relay R90, the rectifier 96 and the conductor C99 to ground, the first-mentioned neutral point between the windings of the repeater 15 being connected to the last-mentioned neutral point between the windings of the repeater 84 by way of a path extending from the first-mentioned neutral point over one of the windings of the repeater 15, the line conductor C81 of the toll

line 80 and the winding 85 of the repeater 84 to the last-mentioned neutral point, and by way of a path extending from the first-mentioned neutral point over another winding of the repeater 15, the line conductor C82 of the toll line 80 and the winding 86 of the repeater 84 to the last-mentioned neutral point. It is noted that the rectifier 96 readily conducts current over the above-traced circuit in the direction indicated, thereby effectively to short-circuit the winding of the relay R95; while the rectifier 91 blocks the passage of current therethrough when current is conducted over the above-traced circuit in the direction indicated. Accordingly, at this time, the relay R95 is not operated and the relay R90 is operated. Upon operating, the relay R90 completes, at RA92 and at RA93, a loop circuit extending between the windings 87 and 88 of the repeater 84 and the windings 65 and 66 of the repeater 64. The last-mentioned loop circuit extends from the conductor C120 by way of the windings 87 and 88 of the repeater 84, the conductor C123, RA93, the conductor C124, the windings 66 and 65 of the repeater 64, the conductor C121 and RA92 to the conductor C120.

After inserting the plug of the cord circuit into the call jack at the operator position 14, the toll operator actuates the talk key in the cord circuit thereat, thereby to complete a loop circuit between the telephone instrument in the cord circuit thereat and the windings of the repeater 15.

At this time a connection is established between the telephone instrument in the cord circuit at the operator position 14 and the toll line 60 extending to the exchange C, in an obvious manner. In the event the toll line 60 is busy at this time, voice frequency current therefrom is diverted by way of the various loop circuits previously traced to the receiver of the telephone instrument in the cord circuit at the operator position 14 and the toll operator thereat hears the conversation.

On the other hand, in the event the toll line 60 is idle at this time, the toll operator at the operator position 14 does not hear a conversation. The toll operator at the operator position 14 then actuates the ring key in the cord circuit thereat, thereby to complete a circuit for conducting alternating ringing current over a portion of the loop circuit extending between the operator position 14 and the repeater 15, thereby to cause ringing current to be induced in the loop circuit extending between the repeaters 15 and 84. The alternating ringing current traversing the last-mentioned loop circuit causes ringing current to be induced in the loop circuit extending between the repeaters 84 and 64; and the alternating ringing current traversing the last-mentioned loop circuit causes ringing current to be induced in the windings 36 and 38 of the repeater 13, thereby to complete a circuit for energizing the winding of the signal 24. The circuit for energizing the winding of the signal 24 extends from the conductor C25 by way of the winding of the signal 24, the switch springs 23 and 22 of the answer jack 20, the conductor C26 and the windings 38 and 36 of the repeater 13 to the conductor C25. The alternating ringing current traversing the winding of the signal 24 causes the signal to be actuated, thereby to indicate to the toll operator at the

operator position 12 that a call is on the toll line 60.

The toll operator at the operator position 12 then answers the call by inserting the plug 51 of the cord circuit 50 thereat into the answer jack 20. When the plug 51 of the cord circuit 50 is inserted into the answer jack 20 the switch springs 22 and 23 are actuated into disengagement, thereby to interrupt the previously traced circuit for energizing the signal 24. The toll operator at the operator position 12 then actuates the talk key in the cord circuit 50, thereby to complete a loop circuit between the telephone instrument in the cord circuit 50 thereat and the windings 36 and 38 of the repeater 13. The last-mentioned loop circuit extends from the conductor C25 by way of the windings 36 and 38 of the repeater 13, the conductor C26, the jack ring 22, the plug ring 53, the talk key and telephone instrument in the cord circuit 50, the plug tip 52 and the jack tip 21 to the conductor C25. At this time a two-way communication connection is established between the operator positions 14 and 12 in the exchanges A and C, respectively.

25 The release of this established connection is primarily under the control of the toll operator at the operator position 14 in the exchange A and is effected when the toll operator thereat withdraws the plug of the cord circuit thereat from 30 the associated call jack, thereby to interrupt the previously traced circuit including the simplex link provided by the toll line 80 and the windings of the repeaters 15 and 84 for energizing the winding of the relay R90, whereupon the relay 35 R90 restores. Upon restoring, the relay R90 interrupts, at RA92 and at RA93, the previously traced loop circuit extending between the windings 87 and 88 of the repeater 84 and the windings 65 and 66 of the repeater 64. Subsequently, 40 the toll operators at the toll operator positions 14 and 12 in the exchanges A and C, respectively, return the talk keys in the respective cord circuits thereat to their normal positions, thereby to disconnect the respective telephone instruments from the associated cord circuits.

45 From the foregoing description of the manner of extending and releasing connections between the exchanges C and A, C and B and A and C, it will be understood that connections may be extended and released between the exchanges A and B, B and A, and B and C, in a similar manner.

More particularly, in order to extend a connection between the exchange A and the exchange 55 B, the toll operator at the operator position 14 inserts the plug of the cord circuit thereat into the proper call jack, thereby to complete a path for connecting the ungrounded negative terminal of a battery, the positive terminal of which is 60 grounded, to a conductor, not shown, extending to the neutral point between the windings of the repeater 15. When the negative terminal of battery is connected to the conductor mentioned, a circuit including a simplex link provided by the toll line 80 and the repeaters 15 and 84 associated therewith for energizing the winding of the relay R95 is completed. The last-mentioned circuit extends from ground by way of the conductor C99, the winding of the relay R95, the rectifier 91 and the conductor C83 to the neutral point between the windings 85 and 86 of the repeater 84, the neutral points between the respective windings of the repeaters 84 and 15 being connected together by way of a simplex circuit including the toll line 80. It is noted that the

rectifier 91 readily conducts current over the above-traced circuit in the direction indicated, thereby effectively to short-circuit the winding of the relay R90; while the rectifier 96 blocks the passage of current therethrough when current is conducted over the above-traced circuit in the direction indicated. Accordingly, at this time, the relay R90 is not operated and the relay R95 is operated.

Upon operating, the relay R95 completes, at RA97 and at RA98, a loop circuit extending between the windings 87 and 88 of the repeater 84 and the windings 77 and 78 of the repeater 74. The last-mentioned loop circuit extends from the conductor C120 by way of the windings 87 and 88 of the repeater 84, the conductor C123, RA98, the conductor C125, the windings 78 and 77 of the repeater 74, the conductor C122 and RA97 to the conductor C120. At this time a connection is established between the toll lines 80 and 70 in a manner similar to that previously explained. The manner of signaling the toll operator at the operator position 16 in the exchange B and the manner of releasing the established connection between the exchanges A and B are the same as previously described.

More particularly, in order to extend a connection between the exchange B and the exchange A, the toll operator at the operator position 16 inserts the plug of the cord circuit thereinto the proper call jack, thereby to complete a path for connecting the ungrounded negative terminal of a battery, the positive terminal of which is grounded, to a conductor, not shown, extending to the neutral point between the windings of the repeater 17. When the negative terminal of battery is connected to the conductor mentioned, a circuit including a simplex link provided by the toll line 70 and the repeaters 17 and 74 associated therewith for energizing the winding of the relay R110 is completed. The last-mentioned circuit extends from ground by way of the conductor C119, the winding of the relay R110, the rectifier 116 and the conductor C113 to the neutral point between the windings 75 and 76 of the repeater 74, the neutral points between the respective windings of the repeaters 74 and 17 being connected together by way of a simplex circuit including the toll line 70. It is noted that the rectifier 116 readily conducts current over the above-traced circuit in the direction indicated, thereby effectively to short-circuit the winding of the relay R115; while the rectifier 111 blocks the passage of current therethrough when current is conducted over the above-traced circuit in the direction indicated. Accordingly, at this time, the relay R115 is not operated and the relay R110 is operated.

Upon operating, the relay R110 completes, at RA112 and at RA113, a loop circuit extending between the windings 77 and 78 of the repeater 74 and the windings 87 and 88 of the repeater 84. The last-mentioned loop circuit extends from the conductor C120 by way of the windings 87 and 88 of the repeater 84, the conductor C123, RA113, the conductor C125, the windings 78 and 77 of the repeater 74, the conductor C122 and RA112 to the conductor C120. At this time a connection is established between the toll lines 70 and 80 in a manner similar to that previously explained. The manner of signaling the toll operator at the operator position 14 in the exchange A and the manner of releasing the established connection between the exchanges B and A are the same as previously described.

More particularly, in order to extend a connection between the exchanges B and C, the toll operator at the operator position 16 inserts the plug of the cord circuit thereinto the proper call jack, thereby to complete a path for connecting the ungrounded positive terminal of a battery, the negative terminal of which is grounded, to a conductor, not shown, extending to the neutral point between the windings of the repeater 17. When the positive terminal of battery is connected to the conductor mentioned, a circuit including a simplex link provided by the toll line 70 and the repeaters 17 and 74 associated therewith for energizing the winding of the relay R115 is completed. The last-mentioned circuit extends from the positive terminal of battery connected to the conductor mentioned to the neutral point between the windings of the repeater 17 and from the neutral point between the windings 75 and 76 of the repeater 74 by way of the conductor C123, the winding of the relay R115, the rectifier 111 and the conductor C119 to ground, the neutral points between the respective windings of the repeaters 17 and 74 being connected together by way of a simplex circuit including the toll line 70. It is noted that the rectifier 111 readily conducts current over the above-traced circuit in the direction indicated, thereby effectively to short-circuit the winding of the relay R110; while the rectifier 116 blocks the passage of current therethrough when current is conducted over the above-traced circuit in the direction indicated. Accordingly, at this time, the relay R110 is not operated and the relay R115 is operated.

Upon operating, the relay R115 completes, at RA117 and at RA118, a loop circuit between the windings 77 and 78 of the repeater 74 and the windings 65 and 66 of the repeater 64. The last-mentioned loop circuit extends from the conductor C122 by way of the windings 77 and 78 of the repeater 74, the conductor C125, RA118, the conductor C124, the windings 66 and 65 of the repeater 64, the conductor C121 and RA117 to the conductor C122. At this time a connection is established between the toll lines 70 and 60 in a manner similar to that previously explained. The manner of signaling the toll operator at the operator position 12 in the exchange C and the manner of releasing the established connection between the exchanges B and C are the same as previously described.

While there has been described what is at present considered to be the preferred embodiment of the invention, it will be understood that various modifications may be made therein without departing from the invention and it is intended to cover in the appended claims all such modifications as fall within the true spirit and scope of the invention.

What is claimed is:

- In a telephone system, an exchange, a switching center, a trunk extending between said exchange and said switching center, first and second lines at said switching center, switching apparatus at said switching center and operative selectively to associate said trunk with said first and second lines for communication thereover,
- apparatus at said switching center and responsive to first and second continuous voltages of different characteristics impressed upon said trunk for controlling selectively the operation of said switching apparatus, and apparatus in said exchange operative to cause said first and second

continuous voltages to be impressed selectively upon said trunk.

2. In a telephone system, an exchange, a switching center, a trunk extending between said exchange and said switching center, first and second lines at said switching center, switching apparatus at said switching center and operative selectively to associate said trunk with said first and second lines for communication thereover, apparatus at said switching center and responsive to first and second voltages of different polarity impressed upon said trunk for controlling selectively the operation of said switching apparatus, and apparatus in said exchange operative to cause said first and second voltages to be impressed selectively upon said trunk.

3. In a telephone system, an exchange, a switching center, a trunk extending between said exchange and said switching center, first and second lines at said switching center, switching apparatus at said switching center and operative selectively to associate said trunk with said first and second lines for communication thereover, apparatus at said switching center and including a circuit network and means controlled in accordance with the direction of current flow in said circuit network for governing selectively the operation of said switching apparatus, a circuit including said trunk for conducting current to said circuit network, a telephone instrument in said exchange, and apparatus in said exchange operative to associate said telephone instrument with said trunk and to complete said circuit and selectively to determine the direction of the current conducted to said circuit network.

4. In a telephone system, an exchange, a switching center, a trunk extending between said exchange and said switching center, first and second lines at said switching center, switching apparatus at said switching center and operative selectively to associate said trunk with said first and second lines for communication thereover, apparatus at said switching center and including a circuit network and means controlled in accordance with the direction of current flow in said circuit network for governing selectively the operation of said switching apparatus, a circuit including said trunk for conducting current to said circuit network, a telephone instrument in said exchange, first and second jacks in said exchange, means including said first jack for operatively associating said telephone instrument with said trunk and for completing said circuit to conduct current in one direction to said circuit network, and means including said second jack for operatively associating said telephone instrument with said trunk and for completing said circuit to conduct current in the opposite direction to said circuit network.

5. In a telephone system, an exchange, a switching center, a trunk having two line conductors and extending between said exchange and said switching center, first and second lines at said switching center, switching apparatus at said switching center and operative selectively to associate said trunk with said first and second lines for communication thereover, apparatus at said switching center and including a circuit network and means controlled in accordance with the direction of current flow in said circuit network for governing selectively the operation of said switching apparatus, means including said trunk and impedance elements in said exchange and at said switching center connected to the line

conductors of said trunk for providing a simplex link, said circuit network having two terminals, one terminal of said circuit network being connected to ground and the other terminal thereof

5 being connected to said simplex link, a telephone instrument in said exchange and having a plug associated therewith, first and second jacks in said exchange and associated with the line conductors of said trunk, said telephone instrument being operatively associated with said trunk when said plug is inserted into either one of said jacks, means controlled by the insertion of said plug into said first jack for connecting the ungrounded positive terminal of a grounded source of current to said simplex link, and means controlled by the insertion of said plug into said second jack for connecting the ungrounded negative terminal of a grounded source of current to said simplex link.

10 6. In a telephone system, an exchange, a switching center, a trunk having two line conductors and extending between said exchange and said switching center, first and second lines at said switching center, switching apparatus at

25 said switching center and operative selectively to associate said trunk with said first and second lines for communication thereover, apparatus at said switching center and including a circuit network and means controlled in accordance with the direction of current flow in said circuit network for governing selectively the operation of said switching apparatus, means including said trunk and impedance elements in said exchange and at said switching center connected to the line

30 35 conductors of said trunk for providing a simplex link, a circuit including said simplex link for conducting current to said circuit network, apparatus in said exchange operative to complete said circuit and selectively to determine the direction of the current conducted to said circuit network, and means in said exchange for projecting alternating signal current over said trunk and the one of said lines associated therewith.

40 45 7. In a telephone system, an exchange, a switching center, a trunk extending between said exchange and said switching center, first and second lines at said switching center, switching apparatus at said switching center and operative

50 55 selectively to associate said trunk with said first and second lines for communication thereover, apparatus at said switching center and including a circuit network and means controlled in accordance with the direction of current flow in said circuit network for governing selectively the operation of said switching apparatus, a circuit including said trunk for conducting current to said circuit network, a telephone instrument in said exchange, apparatus in said exchange operative to associate said telephone instrument with said trunk and to complete said circuit and selectively to determine the direction of the current conducted to said circuit network, and means in said exchange for projecting alternating signal current over said trunk and the one of said lines associated therewith.

60 65 8. In a telephone system, an exchange, a switching center, a trunk having two line conductors and extending between said exchange and said switching center, first and second lines at said switching center, switching apparatus at said switching center and operative selectively to associate said trunk with said first and second lines for communication thereover, apparatus at said switching center and including a circuit network and means controlled in accordance with the direction of current flow in said circuit network for governing selectively the operation of said switching apparatus, means including said trunk and impedance elements in said exchange and at said switching center connected to the line

70 75 conductors of said trunk for providing a simplex link, said circuit network having two terminals, one terminal of said circuit network being connected to ground and the other terminal thereof being connected to said simplex link, a telephone instrument in said exchange and having a plug associated therewith, first and second jacks in said exchange and associated with the line conductors of said trunk, said telephone instrument being operatively associated with said trunk when said plug is inserted into either one of said jacks, means controlled by the insertion of said plug into said first jack for connecting the ungrounded positive terminal of a grounded source of current to said simplex link, and means controlled by the insertion of said plug into said second jack for connecting the ungrounded negative terminal of a grounded source of current to said simplex link.

apparatus at said switching center and operative selectively to perform different switching functions, apparatus at said switching center and including a circuit network and means controlled in accordance with the direction of current flow in said circuit network for governing selectively the operation of said switching apparatus, a circuit including said trunk for conducting current to said circuit network, and apparatus in said exchange operative to complete said circuit and selectively to determine the direction of the current conducted to said circuit network.

9. In a signaling system, a station, a switching center, a trunk line extending between said station and said switching center, first and second lines at said switching center, apparatus at said switching center and responsive to first and second continuous voltages of different characteristics impressed upon said trunk line for selectively associating said trunk line with said first and second lines for signaling thereover, and apparatus in said station operative to cause said first and second voltages to be impressed selectively upon said trunk line.

10. In a signaling system, a station, a switching center, a trunk line extending between said station and said switching center, first and second lines at said switching center, apparatus at said switching center and responsive to first and second voltages of different polarity impressed upon said trunk line for selectively associating said trunk line with said first and second lines for signaling thereover, and apparatus in said station operative to cause said first and second voltages to be impressed selectively upon said trunk line.

11. In a signaling system, a station, a switching center, a trunk line extending between said station and said switching center, first and second lines at said switching center, switching apparatus at said switching center and operative selectively to first and second positions, means responsive to the operation of said switching apparatus to said first position for associating said trunk line with said first line for signaling thereover, means responsive to the operation of said switching apparatus to said second position for associating said trunk line with said second line for signaling thereover, apparatus at said switching center and responsive to first and second voltages of different characteristics impressed upon said trunk line for selectively operating said switching apparatus to said first and second position, and apparatus in said station operative to cause said first and second voltages to be impressed selectively upon said trunk line.

12. In a signaling system, a station, a switching center, a trunk line extending between said station and said switching center, first and second lines at said switching center, switching apparatus at said switching center and operative selectively to first and second positions, means responsive to the operation of said switching apparatus to said first position for associating said trunk line with said first line for signaling thereover, means responsive to the operation of said switching apparatus to said second position for associating said trunk line with said second line for signaling thereover, control apparatus at said switching center and responsive to a voltage of one polarity impressed upon said trunk line for causing said switching apparatus to be operated to said first position and responsive to a voltage of opposite polarity impressed upon said trunk

line for causing said switching apparatus to be operated to said second position, and apparatus in said station operative to cause voltages of said one polarity and of said opposite polarity to be impressed selectively upon said trunk line.

13. In a signaling system, a station, a switching center, a trunk line extending between said station and said switching center, first and second lines at said switching center, relay means at said switching center and operative selectively to first and second positions, means controlled by the operation of said relay means to said first position for associating said trunk line with said first line for signaling thereover and controlled by the operation of said relay means to said second position for associating said trunk line with said second line for signaling thereover, a circuit including said trunk line for energizing said relay means, said relay means being so connected and arranged that it is operated to said first position when it is energized with current traversing said circuit in one direction and is operated to said second position when it is energized with current traversing said circuit in an opposite direction, and apparatus in said station operative to complete said circuit and selectively to determine the direction of the current traversing said circuit.

14. In a signaling system, a station, a switching center, a trunk line extending between said station and said switching center, first and second lines at said switching center, first and second relays at said switching center, means controlled by the operation of said first relay for associating said trunk line with said first line for signaling thereover, means controlled by the operation of said second relay for associating said trunk line with said second line for signaling thereover, a circuit including said trunk line for energizing said first and second relays, said first and second relays being so connected and arranged that said first relay is operated and said second relay is not operated when a current traverses said circuit in one direction and that said first relay is not operated and said second relay is operated when a current traverses said circuit in an opposite direction, and apparatus in said station operative to complete said circuit and selectively to determine the direction of the current traversing said circuit.

15. In a signaling system, a station, a switching center, a trunk line extending between said station and said switching center, first and second lines at said switching center, first and second relays at said switching center, means controlled by the operation of said first relay for associating said trunk line with said first line for signaling thereover, means controlled by the operation of said second relay for associating said trunk line with said second line for signaling thereover, each of said relays having an operating winding, the winding of said relays being connected in series circuit relationship, a first uni-directional current conducting device connected in parallel circuit relationship with the winding of said first relay, a second uni-directional current conducting device connected in parallel circuit relationship with the winding of said second relay, a circuit including said trunk line for energizing the windings of said first and second relays, said relays and said devices being so connected and arranged that the winding of said first relay is effectively energized and the winding of said second relay is effectively short-circuited when a current traverses said circuit

in one direction and that the winding of said first relay is effectively short-circuited and the winding of said second relay is effectively energized when a current traverses said circuit in an opposite direction, and apparatus in said station operative to complete said circuit and selectively to determine the direction of the current traversing said circuit.

16. In a signaling system, a station, a switching center, a trunk line extending between said station and said switching center, first and second lines at said switching center, switching apparatus at said switching center and including a circuit network and means controlled in accordance with the direction of current flow in said circuit network for governing selectively the operation of said switching apparatus, a circuit including said trunk line for conducting current to said circuit network, and apparatus in said station operative to complete said circuit and selectively to determine the direction of the current conducted to said circuit network.

17. In a signaling system, a station, a switching center, a trunk line having two line conductors and extending between said station and said switching center, first and second lines at said switching center, switching apparatus at said switching center and operative selectively to associate said trunk line with said first and second lines for signaling thereover, apparatus at said switching center and including a circuit network and means controlled in accordance with the direction of current flow in said circuit network for governing selectively the operation of said switching apparatus, means including said trunk line and impedance elements in said exchange and at said switching center connected to the line conductors of said trunk line for providing a simplex link, a circuit including said simplex link for conducting current to said circuit network, and apparatus in said station operative to complete said circuit and selectively to determine the direction of the current conducted to said circuit network.

18. In a signaling system, a station, a switching center, a trunk line extending between said station and said switching center, first and second lines at said switching center, switching apparatus at said switching center and operative selectively to associate said trunk line with said first and second lines for signaling thereover, apparatus at said switching center and including a circuit network and means controlled in accordance with the direction of current flow in said circuit network for governing selectively the operation of said switching apparatus, said circuit network having two terminals, one of the terminals of said circuit network being connected to ground and the other terminal thereof being connected to said trunk line, and apparatus in said station operative selectively to connect the ungrounded positive terminal of a grounded source of current and the ungrounded negative terminal of a grounded source of current to said trunk line.

19. In a signaling system, a station, a switching center, a trunk line having two line conductors and extending between said station and said switching center, first and second lines at said switching center, switching apparatus at said switching center and operative selectively to associate said trunk line with said first and second lines for signaling thereover, apparatus at said switching center and including a circuit network and means controlled in accordance with the

direction of current flow in said circuit network for governing selectively the operation of said switching apparatus, means including said trunk line and impedance elements in said station and at said switching center connected to the line conductors of said trunk line for providing a simplex link, said circuit network having two terminals, one terminal of said circuit network being connected to ground and the other terminal thereof being connected to said simplex link, and apparatus in said station operative selectively to connect the ungrounded positive terminal of a grounded source of current and the ungrounded negative terminal of a grounded source of current to said simplex link.

20. In a telephone system, a plurality of exchanges, a switching center, a plurality of trunks respectively extending between said exchanges and said switching center, switching apparatus at said switching center and operative selectively to perform different switching functions, a plurality of control apparatus at said switching center and associated with said switching apparatus, each of said control apparatus including a circuit network and means controlled in accordance with the direction of current flow in said circuit network for governing selectively certain of the operations of said switching apparatus, a plurality of circuits respectively including said trunks for conducting current to the control networks of the respective control apparatus, and apparatus in said exchanges respectively operative to complete respective ones of said circuits and selectively to determine the direction of the current conducted to the circuit networks of the respective control apparatus.

21. In a telephone system, first and second and third exchanges, a switching center, first and second and third trunks respectively extending between said first and second and third exchanges and said switching center, switching apparatus at said switching center, said switching apparatus being so connected and arranged that it is responsive to first and second voltages of different characteristics impressed upon said first trunk for selectively associating said first trunk with said second and third trunks for communication thereover and that it is responsive to first and second voltages of different characteristics impressed upon said second trunk for selectively associating said second trunk with said first and third trunks for communication thereover and that it is responsive to first and second voltages of different characteristics impressed upon said third trunk for selectively associating said third trunk with said first and second trunks for communication thereover, and apparatus in each of said exchanges operative to cause said first and second voltages to be impressed selectively upon the associated trunk.

22. In a telephone system, first and second and third exchanges, a switching center, first and second and third trunks respectively extending between said first and second and third exchanges and said switching center, switching apparatus at said switching center, said switching apparatus being so connected and arranged that it is responsive to first and second voltages of different polarity impressed upon said first trunk for selectively associating said first trunk with said second and third trunks for communication thereover and that it is responsive to first and second voltages of different polarity impressed upon said second trunk for selectively associating said second trunk with said first and third

trunks for communication thereover and that it is responsive to first and second voltages of different polarity impressed upon said third trunk for selectively associating said third trunk with said first and second trunks for communication thereover, and apparatus in each of said exchanges operative to cause said first and second voltages to be impressed selectively upon the associated trunk.

23. In a telephone system, first and second and third exchanges, a switching center, first and second and third trunks respectively extending between said first and second and third exchanges and said switching center, first and second and third switching apparatus at said switching center and respectively associated with said first and second and third trunks, each of said switching apparatus being operative selectively to associate the trunk associated therewith with the other two trunks for communication thereover, first and second and third control apparatus at said switching center and respectively associated with said first and second and third switching apparatus, each of said control apparatus including a circuit network and means controlled in accordance with the direction of current flow in said circuit network for governing selectively the operation of the associated switching apparatus, first and second and third circuits respectively including said first and second and third trunks for conducting current to the circuit networks of the respective control apparatus, and apparatus in said first and second and third exchanges respectively operative to complete said first and second and third circuits and selectively to determine the direction of the current conducted to the circuit networks of said first and second and third control apparatus.

24. In a signaling system, a plurality of stations, a switching center, a plurality of trunk lines respectively extending between said stations and said switching center, switching apparatus at said switching center, said switching apparatus being so connected and arranged that it is responsive to first and second voltages of different characteristics impressed upon any one of said trunk lines for selectively associating said one trunk line with two other of said trunk lines for signaling thereover, and apparatus in each of said stations operative to cause said first and second voltages to be impressed selectively upon the associated trunk line.

25. In a signaling system, a plurality of stations, a switching center, a plurality of trunk lines respectively extending between said stations and said switching center, switching apparatus at said switching center, said switching apparatus being so connected and arranged that it is responsive to first and second voltages of different polarity impressed upon any one of said trunk lines for selectively associating said one trunk line with two other of said trunk lines for signaling thereover, and apparatus in each of said stations operative to cause said first and second voltages to be impressed selectively upon the associated trunk line.

26. In a signaling system, a plurality of stations, a switching center, a plurality of trunk lines respectively extending between said stations and said switching center, a plurality of switching apparatus at said switching center and respectively associated with said trunk lines, each of said switching apparatus being operative selectively to associate the trunk line associated

therewith with two other trunk lines for signaling thereover, a plurality of control apparatus at said switching center and respectively associated with said switching apparatus, each of said control apparatus including a circuit network and means controlled in accordance with the direction of current flow in said circuit network for governing selectively the operation of the associated switching apparatus, a plurality of circuits respectively including said trunk lines for conducting current to the circuit networks of the respective control apparatus, and apparatus in said stations respectively operative to complete respective ones of said circuits and selectively to determine the direction of the current conducted to the circuit networks of the respective control apparatus.

27. In a telephone system, an exchange, a switching center, a first trunk extending between said exchange and said switching center, second and third trunks extending to said switching center, said first trunk including two line conductors, first second and third repeaters at said switching center respectively associated with said first second and third trunks, another repeater in said exchange associated with said first trunk, switching apparatus at said switching center and operative selectively to associate said first repeater with said second and third repeaters, thereby selectively and operatively to connect said first trunk to said second and third trunks, apparatus at said switching center and including a circuit network and means controlled in accordance with the direction of current flow in said circuit network for governing selectively the operation of said switching apparatus, means including said first trunk and said first and other repeaters for providing a simplex link, a circuit including said simplex link for conducting current to said circuit network, a telephone instrument in said exchange, and apparatus in said exchange operative to associate said telephone with said other repeater and to complete said circuit and selectively to determine the direction of the current conducted to said circuit network.

28. In a telephone system, first and second and third exchanges, a switching center, first and second and third trunks respectively extending between said first and second and third exchanges and said switching center, each of said trunks including two line conductors, first and second and third repeaters at said switching center respectively associated with said first and second and third trunks, first and second and third additional repeaters in said first and second and third exchanges and respectively associated with said first and second and third trunks, first and second and third switching apparatus at said switching center and respectively associated with said first-mentioned first and second and third repeaters, each of said switching apparatus being operative selectively to associate the first-mentioned repeater associated therewith with the other two first-mentioned repeaters, thereby selectively and operatively to connect each trunk to the other two trunks, first and second and third control apparatus at said switching center and respectively associated with said first and second and third switching apparatus, each of said control apparatus including a circuit network and means controlled in accordance with the direction of current flow in said circuit network for governing selectively the operation of the associated switching appa-

ratus, means including said first and second and third trunks and said first and second and third first-mentioned and additional repeaters respectively associated therewith for respectively providing first and second and third simplex links, first and second and third circuits respectively including said first and second and third simplex links for conducting current to the respective circuit networks of said first and second and third control apparatus, and apparatus in said first and second and third exchanges respectively operative to complete said first and second and third circuits and selectively to determine the direction of the current conducted to the circuit networks of said first and second and third control apparatus.

29. In a signaling system, a station, a switching center, a first trunk line extending between said station and said switching center, second and third trunk lines extending to said switching center, said first trunk line including two line conductors, first and second and third repeaters at said switching center respectively associated with said first and second and third trunk lines, another repeater in said station associated with said first trunk line, switching apparatus at said switching center and operative selectively to associate said first repeater with said second and third repeaters, thereby selectively and operatively to connect said first trunk line to said second and third trunk lines, apparatus at said switching center and including a circuit network and means controlled in accordance with the direction of current flow in said circuit network for governing selectively the operation of said switching apparatus, means including said first trunk line and said first and other repeaters for providing a simplex link, a circuit including said simplex link for conducting current to said circuit network, and apparatus in said station operative to complete said circuit and selectively to determine the direction of the current conducted to said circuit network.

30. In a signaling system, a station, a switching center, a first trunk line extending between said station and said switching center, second and third trunk lines extending to said switching center, said first trunk line including two line conductors, first and second and third repeaters at said switching center respectively associated with said first and second and third trunk lines, another repeater in said station associated with said first trunk line, switching apparatus at said switching center and operative selectively to associate said first repeater with said second and third repeaters, thereby selectively and operatively to connect said first trunk line to said second and third trunk lines, apparatus at said switching center and including a circuit network and means controlled in accordance with the direction of current flow in said circuit network for governing selectively the operation of said switching apparatus, means including said first trunk line and said first and other repeaters for providing a simplex link, said circuit network having two terminals, one terminal of said circuit network being connected to ground and the other terminal thereof being connected to said simplex link, and apparatus in said station operative selectively to connect the ungrounded positive terminal of a grounded source of current and the ungrounded negative terminal of a grounded source of current to said simplex link.

31. In a signaling system, a plurality of stations, a switching center, a plurality of trunk lines respectively extending between said stations and said switching center, each of said trunk lines including two line conductors, a plurality of repeaters at said switching center respectively associated with said trunk lines, a plurality of additional repeaters in said stations and respectively associated with said trunk lines, a plurality of switching apparatus at said switching center and respectively associated with said first-mentioned repeaters, each of said switching apparatus being operative selectively to associate the first-mentioned repeater associated therewith with two other of the first-mentioned repeaters, thereby selectively and operatively to connect each trunk line to two other trunk lines, a plurality of control apparatus at said switching center and associated with said switching apparatus, each of said control apparatus including a circuit network and means controlled in accordance with the direction of current flow in said circuit network for governing selectively the operation of the associated switching apparatus, means including said trunk lines and said first-mentioned and additional repeaters respectively associated therewith for respectively providing a plurality of simplex links, a plurality of circuits respectively including said simplex links for conducting current to the control networks of the respective control apparatus, and apparatus in said stations respectively operative to complete respective ones of said circuits and selectively to determine the direction of the current conducted to the circuit networks of the respective control apparatus.

32. In a telephone system, an exchange, a switching center, a trunk extending between said exchange and said switching center, first and second lines at said switching center, switching apparatus at said switching center, said switching apparatus being operable selectively to associate said trunk with said first and second lines for communication thereover and restorable to disassociate said toll trunk from said first and second lines, apparatus at said switching center and responsive to the impression of first and second continuous voltages of different characteristics upon said trunk for causing selective operations of said switching apparatus and responsive to the removal of said first continuous voltage or said second continuous voltage from said toll trunk for causing restoration of said switching apparatus, and means in said exchange selectively operable to cause said first and second continuous voltages to be impressed selectively upon said trunk and to cause said first continuous voltage or said second continuous voltage to be removed from said trunk.

33. In a telephone system, an exchange, a switching center, a trunk extending between said exchange and said switching center, first and second lines at said switching center, switching apparatus at said switching center, said switching apparatus being operable selectively to associate said trunk with said first and second lines for communication thereover and restorable to disassociate said trunk from said first and second lines, apparatus at said switching center and responsive to the impression of first and second continuous voltages of different characteristics upon said trunk for causing selective operations of said switching apparatus and responsive to the removal of said first continuous voltage or said second continuous voltage from said trunk

for causing restoration of said switching apparatus, means in said exchange selectively operable to cause said first and second continuous voltages to be impressed selectively upon said trunk and to cause said first continuous voltage or said second continuous voltage to be removed from said trunk, and additional means in said exchange

for projecting alternating ringing current over said trunk and the one of said lines associated therewith while either said first continuous voltage or said second continuous voltage is impressed upon said trunk.
